UNITED STATES PATENT OFFICE

CHARLES FISCHER, OF NEW YORK, N. Y.

GOOGLES

Application filed July 11, 1927. Serial No. 204,774.

My invention relates to eye goggles such as are used in aviation or the like, and more particularly to the goggle frame and to means for connecting the goggles together, the said connecting means also serving as a means for separately and detachably pivoting the bridge of the goggles thereto. My invention also relates to the means whereby the window of the goggle, while normally held firmly in position, may be readily removed and replaced, if desired.

One of the objects of my invention is to provide simple, improved means for detachably connecting the frames of each goggle at their inner ends and separately and detachably pivoting the bridge thereto. These means provide a firm construction and permit the rapid assembly of the goggles.

Another object of the invention is to provide an improved goggle frame and means carried by a frame of each goggle for normally securing the outer end of one frame to the outer end of the other frame, so as to assist in firmly holding the windows of the goggles in position, said means comprising a releasable latch, which permits removal and substitution of a window, as desired, the latch being provided with adjustable means so as to prevent rattling of the window in the frames, provide a dust-proof joint and so as to accomodate windows of varying thickness.

With the above and other objects in view, my invention consists in the parts, improvements and combinations more fully pointed out hereinafter.

Turning now to the drawings, which illustrate one embodiment of the invention:

Figure 1 is a top plan view of the goggles, partly in section.

Figure 2 is a front elevation of part of the goggles, showing the bridge piece and pivot pins connecting the goggles together.

Figure 3 is an enlarged sectional view, showing the detachable bridge for connecting the goggles.

Figure 4 is a sectional view taken on line 4-4 of Figure 3.

Figure 5 is a detail view of the main frame of a goggle forming part of the connecting

means, showing the standard which standard passes thru a slot in the main frame.

Figure 6 is a detail view of the inner end of the window frame, showing the slotted portion, which fits over the standard of the main frame.

Figure 7 is a detail view of the parts of the bridge connecting means, about to be assembled.

Figure 8 is a detail cross-section, showing one embodiment of the latch for releasably and adjustably securing the window frame to the main frame of the goggle.

Figure 9 is a detail sectional view of the latch shown in Figure 8, the latch being shown open.

Figure 10 is a detail view of the loop which is secured to the main frame and to which the head band is connected.

Figure 11 is a view of the main frame of the goggle provided with a folded edge so as to form an integral shelf against which the window rests.

Figure 12 is a cross sectional view showing the main frame and window shelf.

Figure 13 is a cross sectional view showing another form of main frame and window shelf.

Figure 14 is a sectional detail view of another embodiment of the invention, showing a releasable latch carried by the outer portion of the window frame with a screw for releasably and adjustably securing the window frame to the main frame of a goggle.

Figure 15 is a sectional detail view of the latch, showing the tapered screw head for adjusting the latch.

Figure 16 is a side elevation of the latch, shown in Figures 14 and 15, provided with elongated, lost-motion openings to permit movement of the window frame, when closing the window.

In the drawings, the goggles are shown comprising a pair of eyecups 1, each eyecup consisting of a main frame 2, and a window frame 3, which are adapted to receive a window 4. The form of the frame member corresponds to the form of the windows, which are approximately oval in shape and convexly curved. By using an outwardly

convexely curved window, better vision is obtained and there is no refraction when the light passes through the window. The depth of the main frames 2, is such that the window will be positioned the proper distance from the eye of the wearer, the frames being preferably made of sheet metal or other suitably light and strong material. Each main frame 2, is faced on its inner side 5, with rubber 6, or like material, so that the goggles will not irritate the wearer and at the same time enable them to insure a tight fit and prevent dust from entering the goggle. The rubber guard 6, is stitched to the main frame by stitches 7. The curvature of the eyecups is such so as to properly fit the eye. Ventilating openings 8, 9, are also provided for each goggle.

In accordance with the invention, each 20 main frame member is provided with an integral shelf or window supporting rim. The metal edge surrounding the window opening in the eye cup is upwardly inclined at 8a so as to form an acute angle with the main frame 25 and so as to provide a transversely projecting shelf 8b on which the curved window seats itself. In the form shown in Figure 12 the metal edge is reversely bent and the shelf projects inwardly, whereas in the form shown 30 in Figure 13, the edge of the frame is bent so as to provide an upstanding edge 8c of substantially the same thickness and so that the shelf 8d projects outwardly. In each case, the shelf is made, when the frame is 35 pressed into shape by dies. The flanged portion of the frame thus provides a window receiving frame, whose shelf secures an air tight fit for the window and whose flanged edge produces a strong frame in which the 40 curved window fits. As will be seen, the window frame 3 clamps the curved window to the shelf on the main frame 2 by a releasable latch hereinafter described.

Means are provided for swingably joining 45 the main frame and window frame together at their inner portions. Each main frame 2, is slotted at 10, so as to receive a mounting standard 11, see Figure 5. The standard 11, is provided with a loop and is preferably 50 made of a U-shaped strip of metal. Its rounded portion projects beyond the main frame 2, while its free ends are bent at right angles and brazed or otherwise secured to the under side of the inner portion of the 55 main frame 2. The inner end of each of the window frames 3, is formed with an enlarged rearwardly extending flange 12, which is slotted at 13, see Figure 6. The slot in the flange 12, is adapted to receive the mounting 60 standard 11, of the main frame of each goggle. The main frame and the window frame are thus detachably joined together.

Means are provided for pivotally connecting the goggles together. In the form shown 65 in the drawings these means comprise a

bridge or nosepiece 14, see Figures 1 and 7, provided with a central vertical section 15, and an upper and a lower crosspiece 16, 17, respectively, the bridge being cut-out at 18, so as to receive the standard 11, of each main 70 frame, each of which passes through and projects beyond the opening of the respective window frame. The upper and lower horizontal crosspieces 16, 17, are bent at each end thereof, at 18 and 19, respectively, so as 75 to form loops (see Figure 7). Pivot pins 20, are provided, see Figures 2, 3, and 7, which pass thru the loops of the bridge, and thru the standard 11, of the main frame. The goggles may thus be pivotally connected together. 80

Means are provided for normally securing the outer ends of the window frames to the outer ends of the main frames of each goggle, the said means holding the window in position and being releasable, so that a new window may be substituted. The clamping pressure between the window frame and the main frame may be increased or decreased; rattling of the windows in the frames is prevented, a dust-proof joint is provided between the frames and windows of varying thickness may be accommodated. 90

In the embodiment of the invention shown in Figures 8 to 10, a loop member 21, to the 95 loop of which the head band is connected, made of a strip of metal reversely folded on itself, is secured to the outer portion of each of the main frames of the goggle at each side of the goggle, preferably by means of rivets passing thru holes 22 into the frame. A releasable latch 23, pivoted at 24, to the window frame, carries a screw 25, at its free end. The latch is provided with an opening 26, which cooperates with a circular groove in the stem of the screw 25, near its end, the opening 26 being, at first, of circular form. After inserting the screw into the opening 26, with its groove in registering relation with the opening, the end of the latch is compressed so as to compress and elongate the opening thus retaining and holding the screw on the latch without interfering with the rotational movement of the screw. The loop member is bent at 22a so as to present the screw opening 28 to the screw 25 in the direction of movement of the screw when the latch is closed. To shut the window frame, it is closed by hand against the main frame and the screw is then screwed thru hole 28, into 100 the loop member. The pivoted latch with its screw constitute an adjusting means for 105 adjustably securing the window frame to the main frame. 110

The arcuate movement of the screw, and 115 the straightening of the flexible swinging link of the latch, from the curved form shown in Figure 9 to the straight form shown in Figure 8, ensure a tight adjusted fit between the window and its supporting shelf. The head 120

band is connected to the loop member 21, and need not be detached to open the window frame.

In the second embodiment of the invention, the latch forming part of the securing means is provided with an adjusting tapered head and screw, and the frames may thus be adjustably secured together.

As shown in the drawings (Figures 14, 15, 16) a latch 31, is suitably secured to the outer end of each window frame 3. Each latch comprises one piece of spring metal, bent so as to form an outer strip 31a, provided with a tapered head 32, having an eye 33, and an under strip 34, see Figures 14 and 15. Both the outer strip 31a and the under strip 34, are provided at 35, 36, respectively, with elongated, lost-motion openings, which receive a screw 37. The screw 37, is provided with a tapered head, which fits against the tapered head 32 of the latch. The thread of the screw 37, passes thru the elongated, lost-motion openings of the latch and enters the screw hole provided at 38, in the main frame 25 of each goggle. By screwing down the tapered head of the screw, it will contact with the tapered head of the latch, and will slide the latch along the main frame (this movement being permitted by the elongated openings 35, 36 of the latch), and when the screw is forced home the two frames are firmly held in position. By withdrawing the screw, the two frames may be readily separated as for the removal of the window.

The eye 33 of the tapered head 32, of each latch is adapted to receive the ends of the head band, which holds the goggles in place, when in use.

Having thus described the invention and its construction, its operation will be clear. It will be understood that changes may be made in carrying the invention into effect without departing from the principles thereof.

What I claim is:

1. Eye goggles comprising in combination, a pair of eyecups, each eyecup having a main frame and a swingable window frame, a connecting bridge, the inner end of each of said window frames being formed with an enlarged rearwardly extending flange having an opening, and the inner end of each of said main frames being provided with a standard passing thru and projecting beyond said opening, for swingably joining the frames together.

2. Eye goggles comprising in combination a pair of eyecups, each eyecup having a main frame and a window frame, a connecting bridge, the inner end of each window frame being formed with an enlarged rearwardly extending flange having an opening, and looped standards attached to the main frames passing thru and projecting beyond said openings, for swingably joining the frames

together and means for pivotally securing said connecting bridge to the main frame standards of each goggle.

3. Eye goggles comprising in combination, a pair of eyecups, each eyecup having a main frame and a window frame, a connecting bridge provided with crosspieces, cut-out portions between the crosspieces, mounting standards, each carried by one frame of each goggle the inner end of each of said window frames being formed with an enlarged rearwardly extending flange having an opening through which one of said standards passes and projects beyond, said mounting standards arranged to enter the cut-out portion of the connecting bridge, and pivot pins passing thru said cross-pieces and mounting standards, so as to pivotally secure the goggles together.

4. Eye goggles comprising in combination a pair of eyecups, each eyecup having a main frame and a window frame swingably joined together at their inner ends, a connecting bridge, said bridge comprising a central member and an upper and a lower crosspiece, with cut-out portions between them, each of said crosspieces being bent at each end to form loops, mounting standards carried by the inner end of the main frame of each goggle, said mounting standards arranged to enter the cut-out portions between the crosspieces of the connecting bridge, and pivot pins passing thru the loops in the connecting bridge and engaging the mounting standards so as to pivotally connect each eyecup to the connecting bridge.

5. Eye goggles comprising in combination, a pair of eyecups, each eyecup having a main frame and a window frame, said main frame being provided with a slot, a looped standard passing thru said slot, the free ends of said standard being secured to the inner side of the main frame, each of said window frames being formed with an enlarged rearwardly extending flange having an opening adapted to receive a main frame standard, a connecting bridge having upper and lower crosspieces and central cut-out portions, said cut-out portions adapted to receive the standards of the main frames, and pivot pins passing thru the bridge and engaging each standard so as to pivotally connect the goggles together.

6. Eye goggles comprising in combination, a pair of eyecups, each eyecup having a main frame and a window frame, a connecting bridge for the eyecups and a latch mounted at the outer end of each eye goggle for releasably securing the window frame at the outer end of the main frame, the said latch provided with an adjusting screw for adjustably securing the window frame to the main frame.

7. Eye goggles comprising in combination, a pair of eyecups, each eyecup having a main frame and a window frame, a connecting bridge for the eyecups, a loop member to

which the head band may be secured and a latch for releasably securing the window frame to the main frame, the said latch provided with an opening and a screw passing thru said opening, for adjustably securing the window frame to the main frame.

5 8. Eye goggles comprising in combination, a pair of eyecups, each eyecup having a main frame and window frame, a connecting bridge, a loop member and a latch having a pivoted link carried by each window frame at the outer end for releasably securing the window frame to the main frame, the said link carrying a screw, which is adapted to engage an opening carried on the main frame for adjustably securing the window frame to the main frame.

10 9. Eye goggles comprising in combination, a pair of eyecups, each eyecup having a main frame and a window frame, a connecting bridge, a loop member carried by the outer end of each main frame to which the head band may be secured, the said loop member provided with a screw opening, a pivoted link 15 pivoted to each window frame at its outer end and carrying a screw at its free end adapted to engage the said screw opening, for adjustably securing the window frame to the main frame of the goggles.

20 30 In testimony whereof, I have signed my name to this specification.

CHARLES FISCHER.
